United States Patent Office

Des. 227,894
Patented July 24, 1973

227,894

ELECTRICAL COUPLER

Richard L. Double, 1926 Roxanne Ave.,
Long Beach, Calif. 98015

Filed June 10, 1971, Ser. No. 152,015

Term of patent 14 years

Int. Cl. D13—03

U.S. Cl. D26—1 C

FIG. 1 is an isometric view of my new electrical coupler design showing the front end and one side thereof;

FIG. 2 is a view showing the front end of my new coupler design;

FIG. 3 is a view showing one side of my new design;

FIG. 4 is a view showing the other side of my new design;

FIG. 5 is a view of the top of my new design;

FIG. 6 is a bottom view of my new design; and

FIG. 7 is a view of the other end of my new design.

I claim:

The ornamental design for an electrical coupler, as shown.
